UNITED STATES PATENT OFFICE.

GEDEON THOMMEN, OF WALDENBURG, SWITZERLAND.

WATCH.

SPECIFICATION forming part of Letters Patent No. 289,728, dated December 4, 1883.

Application filed May 31, 1883. (Model.) Patented in Germany February 15, 1879, No. 6,878; in France February 24, 1879, No. 129,282, and in Belgium March 15, 1879, No. 47,522.

To all whom it may concern:

Be it known that I, GEDEON THOMMEN, a citizen of Switzerland, and a resident of Waldenburg, near Basel, Switzerland, have invented certain Improvements in Watches, (for which I have obtained German Letters Patent No. 6,878, February 15, 1879; French Letters Patent No. 129,282, February 24, 1879, and Belgian Letters Patent No. 47,522, March 15, 1879,) of which the following is a specification.

My invention relates to certain improvements in the construction of watches, with more special reference to the manner of securing the cannon-pinion on the axis of the pinion of the center-wheel, and to the devices for throwing the hand setting and winding mechanism into and out of gear, as more fully described hereinafter.

In the accompanying drawings, Figure 1 is a view, drawn to an enlarged scale, of sufficient of a watch to illustrate my invention. Fig. 2 is a similar view, showing the rocking lever carrying the gears and separate from its operating devices. Fig. 3 is a view showing the locking-lever. Fig. 4 represents in different views the cannon-pinion and the devices for mounting it on the axis of the center-wheel. Figs. 5, 6, and 7 are views illustrating the construction of the spring-pawl for the ratchet-wheel of the mainspring.

The operative parts of the watch are mounted, as usual, on the front and back plates, *m* and *m'*, *h* being the rocking lever, carrying at opposite ends gear-wheels *f* and *g*, gearing into the same intermediate wheel, *h'*, to which motion is imparted by the usual winding-stem, *s*, either to wind up the spring or to set the hands, according to the position to which the lever *h* has been adjusted. A spring, *p*, acts on one end of this lever, to keep it normally in the position shown in full lines, Fig. 1, with the pinion *g* in gear with the ratchet-wheel *i* on the barrel of the mainspring, so that the turning of the winding-stem will wind up the spring. When the lever *h* is moved to the position indicated by dotted lines in Fig. 1, the wheel *g* will be thrown out of gear with the wheel *i*, while the pinion *f*, at the opposite end of the lever, will be thrown into gear with the wheel *k*, for transmitting motion to the minute and hour hand pinions to set the hands.

On referring to Fig. 4, illustrating the method of mounting the cannon-pinion *a*, it will be seen that this pinion is provided with an internal undercut or dovetailed annular recess, 55 *r*, into which is inserted a spiral spring, *e*, the latter retaining its position by its elasticity. On the pole *d* of the center-wheel *c* is cut an annular recess, into which the inner face of the spring *e* slips, to retain the cannon-pinion 60 *a* when the latter has been placed in position on the tapered pole *d*.

The rocking lever *h*, Fig. 1, is moved into the hand-setting position by means of the bent lever *n*, which is pivoted to the plate *m* at *n'*, 65 and has its outer end projecting outside the case, so that it may be pulled outward to the position indicated by dotted lines in Fig. 1. This lever *n* is provided with a nose, *n''*, acting on an inclined or cam face on the edge of the 70 lever *h*, so that when the said lever *n* is pulled outward, as shown by dotted lines, that end of the rocking lever *h* will be pressed downward against the action of the spring *p*, to throw the pinion *f* into gear with the wheel *k*. To maintain the lever *n* in its inner or normal position, a spring, *o*, acts on a nose, *n'''*, on the lever, the 75 said nose bearing such a relation to the pivoting center of the lever that when the latter is pulled outward to the position shown in Fig. 80 3 the pressure of the spring will be toward the pivot, or on what may be termed a "dead-center," so that there will be then no tendency to return the lever to its normal position; but as soon as the lever *n* is pressed inward a little, 85 the spring *o* will begin to act. One end of the rocking lever *h* is forked, and between these forks is a pin, *l*, secured to the plate *m* in such a position that it will limit the extent of motion of the said lever to insure the gearing of 90 the pinions *f* and *g*, with their corresponding wheels, only to the proper extent.

The spring-pawl *q* for the barrel of the mainspring is constructed as shown in Figs. 5, 6, and 7. It is provided with a pivot-pin, *q'*, 95 passing through the plate *m*, and also has secured to it one end of a steel spring-wire, *q'*, which passes freely through an opening or slot in the front plate, and has its opposite end secured to the back plate, being thus at right 100 angles to the plane of movement of the pawl. When the end of the pawl lies between the

teeth of the wheel i , Fig. 5, the spring-wire g is straight; but when the pawl is moved outward, the spring-wire is bent, which tends to press the pawl inward into gear with the teeth.

5 I claim as my invention—

1. The combination of the axis of the center-wheel having an annular groove, d' , with the cannon-pinion having an annular undercut recess, r , and a spring, e , adapted to the corresponding recess and groove, to maintain the cannon-pinion in position, substantially as set forth.

2. The combination of the rocking lever h ,

having a cam-edge, and the spring o , with the lever n , acting on the said rocking lever, and having a nose, n^3 , to be acted on by the said spring in the relation substantially as described, whereby the nose will be on a dead-center when the lever n is in its open position.

In testimony whereof I have signed my name 20 to this specification in the presence of two subscribing witnesses.

GEDEON THOMMEN.
